PISTON RING

Ralph R. Teetor, Hagerstown, Ind., assignor to
 The Perfect Circle Company, Hagerstown, Ind.,
 a corporation of Indiana

Application December 22, 1939, Serial No. 310,480

9 Claims. (Cl. 309—45)

My invention relates to piston rings for internal combustion engines.

More particularly, my invention relates to improvements in the type of ring which comprises a pair of thin, flat, split rails adapted to engage the cylinder wall, and a spacer-expander adapted to space the rails axially apart and to expand the rails radially.

The principal objects of my invention are to provide an improved spacer-expander and improved means for preventing undue relative rotation between the spacer-expander and the rails.

Other objects and advantages will become apparent as this description progresses and by reference to the drawing wherein—

Fig. 1 is a horizontal section through the groove of a piston and illustrating a ring structure embodying my invention mounted therein, the ring structure being shown in the condition which it assumes when confined within the cylinder of the engine;

Fig. 2 is an enlarged sectional view of the structure shown in Fig. 1, the same being illustrated in operative relation to the cylinder wall;

Fig. 3 is a perspective view of a portion of the spacer-expander; and

Fig. 4 is a perspective view of the ends of one of the rails.

The ring is adapted to be mounted in the oil groove 1 of a piston 8 of an internal combustion engine. The piston, which may be of any desired structure, is mounted within the cylinder wall 9, as is well understood.

The ring structure comprises two flat, thin split rails 11 and 12, preferably formed of steel, and a spacer-expander designated generally by the reference numeral 13. The rails 11 and 12 are split at 11^a and 12^a respectively, as shown in Fig. 1, in which the rail 11 is illustrated broken away to disclose the end portions of the rail 12.

The spacer-expander 13 comprises a member of thin spring ribbon or strip, such as steel, and is constructed and shaped to space the rails apart and also expand them radially to press the outer peripheries of the rails against the cylinder wall. The spacer-expander is of generally polygonal form having side sections 14 and hump portions 15 between and joining the ends of the side sections. The ends of each side section 14 are slightly bowed outwardly to form shallow curved ribs 16. The central and end portions of the side sections are but slightly less in width than the width of the piston groove 1. The connecting humps 15 are semi-circular and are of lesser width than the side portions. The spacer-

expander is split at the center of one of the humps, as indicated at 13^a.

The central portions of the side sections 14 seat against the bottom of the ring groove 1 and the vertical ridges 16 at the ends of the side sections engage the inner peripheries of the rails, the spacer-expander thus acting to expand the rails radially against the cylinder wall. The humps 15 project between the rails and serve to space and maintain the rails apart. The edges of the humps 15 are straight and parallel to each other and also to the adjacent parallel faces of the rails 11 and 12, so that the spacer-expander does not exert any axial pressure against the sides of the rails.

Each edge of each side section 14 is provided with a notch which gradually increases in depth from the central portion to one of the ribs 16, the notch 19 being of greatest depth adjacent the rib. These notches serve a dual function. They permit the excess oil, scraped from the cylinder walls by the rails, to pass behind the spacer-expander and then through drain openings 20 in the piston, back to the crank case of the engine. The notches also permit the spring side sections 14 to flex uniformly from their central portions to their ends without placing any undue flexing stress at any point throughout the length of the side section. The side sections operate substantially independently of each other as the humps are free to bend as the sides are flexed during operation of the engine. The contacting area of each side section 14 with the bottom of the piston groove is comparatively small, because my structure permits this area to be about one-half of the contacting area of each side section of the conventional form of expander which is entirely located between the ring or rails and the bottom of the piston groove. Thus I provide improved spring action and also ample draining through the drain openings 20 which are in portions of the side sections beyond the central contacting area.

It is the practice of some engine manufacturers to machine the bottom of the piston groove, and in some instances this operation has resulted in forming a square annular fillet or ridge 18 in one or both corners of the groove, as illustrated in Fig. 2. I have found that if the central portions of the side sections 14 of the spacer-expander are rectangular, these portions adjacent their edges seat against the fillet and become twisted or locked in position, with attendant defective operation of the ring. To overcome this difficulty, I bevel the inner corners (as

at 17, Fig. 2) of the stock from which the spacer-expander is formed, so that the fillets do not interfere with the spacer-expander. The edges of the humps 15, however, are not beveled, but are horizontal and parallel being so formed when the stock is cut away to reduce the width of the portions forming the humps.

It is desirable to support to a considerable extent the ends of the rails and to also prevent undue rotational movement between the rails and the spacer-expander. To accomplish these ends, I provide on each rail to one side of its joint 11^a or 12^a struck-out tabs or lugs 21 and 21^a which extend circumferentially and toward each other and are inclined to the plane of the rail. In assembling the spacer-expander and the rails, the lugs 21 and 21^a of each rail are positioned on opposite sides of a full hump 15 of the spacer-expander. Preferably the lugs of the one rail are located on both sides of the first full hump to one side of the joint or split 13^a and the lugs of the other rail are located on both sides of the first full hump on the other side of the joint 13^a, as shown in Fig. 1. Any undue rotation of the rail with respect to the spacer-expander is prevented as the rounded end of one of the lugs 21 and 21^a strikes the side of the adjacent hump.

I claim:

1. In a piston ring structure adapted for use in a ring groove of a piston of an internal combustion engine comprising a pair of thin rails adapted to be mounted along the opposite sides of the ring groove, the rails being split to provide rail joints and each rail having two projections adjacent the joint, and a spring spacer-expander means having expanding portions adapted to engage the inner peripheries of the rails to expand the same and also having spacing portions extending between the rails to space and maintain the rails apart, the projections on the rails being adapted to engage adjacent spacing portions to prevent material relative movements between the rails and the spacer-expander.

2. A piston ring structure adapted for use in a ring groove of a piston of an internal combustion engine, comprising a pair of thin, flat rails adapted to be mounted along the opposite sides of the ring groove, the rails being split to provide rail joints and each rail having two integral inclined projections, and a spring spacer-expander of ribbon metal having sides, the ends of which are adapted to engage the inner peripheries of the rails to expand the same, and also having humps connecting the ends of said sides and extending between the rails to space and maintain the rails apart, the projections on each rail being adapted to engage adjacent humps to prevent material relative movements between the rails and the spacer-expander.

3. A piston ring structure adapted for use in a ring groove of a piston of an internal combustion engine, comprising a pair of thin, flat rails adapted to be mounted along the opposite sides of the ring groove, the rails being split to provide rail joints and each rail having two circumferentially disposed and oppositely extending integral projections inclined to the plane of the rail, and a spring spacer-expander of thin metal having sides, the ends of which are adapted to engage the inner peripheries of the rails to expand the same, and also having humps connecting the ends of said sides and extending between the rails to space and maintain the rails apart, the projections on each rail being adapted to be located on

opposite sides of one of said humps to prevent material relative movement between the rails and the spacer-expander.

4. A spacer-expander for piston ring structure having thin, split rails axially spaced apart with their outer peripheries adapted to engage the cylinder wall, which comprises a thin spring ribbon member having side sections, the central portions of which are adapted to seat upon the bottom of a piston ring groove and the ends of which have outwardly bowed shallow ribs adapted to engage the inner peripheries of the rails to expand the same, and circumferentially spaced portions of reduced width and connecting the ends of the side sections and adapted to extend between the rails to support and maintain the latter in substantially uniform axially spaced relation.

5. A spacer-expander for piston ring structure having thin, split rails adapted to be axially spaced apart in a piston groove with their outer peripheries adapted to engage the cylinder wall, which comprises a thin spring ribbon member of generally polygonal shape and having side sections and connecting hump portions, the side sections having central portions with a width but slightly less than that of the piston groove and being adapted to seat upon the bottom of the piston groove, and the side sections having end portions with a width substantially the same as that of the central portions and being adapted to engage the inner peripheries of the rails, and the edges of the side sections being provided with staggered notches of gradually increasing depth from the central portions to the end portions with the greatest depth adjacent the end portions to provide uniform spring action and oil drainage, and the hump portions being connected to the ends of the side sections and being of reduced width and adapted to extend between the rails to support and maintain the latter in substantially uniform axial spaced relation.

6. A thin, flat, split rail for use with an expander having humps, comprising: an annular member having a pair of struck-out circumferentially spaced tabs arranged at an angle relative to the plane of said member and adapted to cooperate with the humps of an expander to prevent undue relative rotational movement between said rail and expander.

7. A thin, flat, split rail for use with a polygonal expander having humps, comprising: an annular member having a pair of tabs struck out along the inner peripheral edge thereof, said tabs being inclined relative to the plane of said member and converging toward each other, said tabs being spaced sufficiently far apart circumferentially to receive the hump of an expander therebetween.

8. A piston ring structure comprising a thin, flat rail adapted to be mounted adjacent one side wall of a piston ring groove, said rail being radially split and having a pair of inclined converging tabs struck out along the inner peripheral edge thereof, and a resilient generally polygonal expander element having side portions and humps connecting said side portions, said side portions being of an axial width slightly less than that of the ring groove in which the same is to be mounted and said humps being reduced in axial width an amount at least equal to about the axial thickness of said rail, said tabs being spaced apart circumferentially a distance sufficient to receive one of said humps therebetween to prevent undue relative rotation between said rail and expander.

9. A piston ring structure comprising a resilient member having side portions and humps connecting said side portions, said side portions having an axial width slightly less than that of the ring groove in which the same is to be mounted, thin flat rail means adapted to be mounted adjacent one side wall of the piston ring groove, said rail means being radially split and having a pair of tabs struck out along the inner edge

5 thereof and arranged at an angle to the plane of said rail means, said humps being of less axial width than said side portions by an amount equal to about the axial thickness of said rail means, said tabs being adapted to cooperate with said humps to prevent undue relative rotation between said expander member and said rail means.

RALPH R. TEETOR.
